COMBINATION STORING AND DISPENSER
CONTAINER FOR LIQUEFIED GAS

Ransom P. Skinner and Richard M. Poorman,
Indianapolis, Ind.

Application December 3, 1958, Serial No. 53,633

Term of patent 14 years

(Cl. D58—17)

The figure is a top perspective view of a combination storing and dispenser container for liquefied gas, showing our new design. The side not shown is the same as the side shown.

We claim:

The ornamental design for a combination storing and dispenser container for liquefied gas, substantially as shown and described.
